UNITED STATES PATENT OFFICE.

JOSEF HUTTER, OF NEW YORK, N. Y.

BOTTLE-OPENER.

1,199,272.

Specification of Letters Patent. Patented Sept. 26, 1916.

Application filed July 7, 1915. Serial No. 38,601.

To all whom it may concern:

Be it known that I, JOSEF HUTTER, a subject of the Emperor of Austria-Hungary, and resident of New York, in the county 5 of New York and State of New York, have invented certain new and useful Improvements in Bottle-Openers, of which the following is a specification.

The device forming the subject matter of 10 the present invention is an improvement in opening means for bottle closures and consists in combined, in one integral piece, parts of great simplicity and efficiency for performing the desired results.

15 The drawings illustrate in Figure 1, a side elevation of a bottle with its stopper and a cross section in line 1—1 of Fig. 2, of the bottle opener, Fig. 2 is a plan view of the opener, and Figs. 3 and 4, are a side elevation and a plan view, respectively, of a bottle opener combined with a cork screw.

20 A blank, of sheet material of sufficient strength and rigidity, such as is possessed by sheet steel, is punched by means of suitable dies, so as to form a handle 1, having a pair of prongs 2, at one end thereof. The blank, in the same punching operation, is also formed with the lifting shoulder 3, and the lever yoke 4. The shoulder is then 25 beveled, as shown, to a relatively sharp engaging edge and the yoke is bent, first substantially at right angles to the plan of the blank, and then again in a plane about parallel thereto. The prongs are slightly 30 curved, to better engage the neck of the

bottle and the yoke is similarly bent to produce a more rigid supporting lever.

The device may be provided with a cork screw 5, pivoted at 6, or any other tool, useful in opening bottles, such as are closed 40 with corks, etc.

In the operation of the device, the prongs engage the neck of the bottle, the yoke rests on top of the bottle stopper, the shoulder engages the flange of the stopper, and by a 45 lifting movement of the handle, the stopper is removed.

I claim:

A bottle opener comprised of a single piece of sheet metal including a flat handle, 50 a pair of guide prongs suited to a bottle neck formed at one end and in the plane of said handle, said prongs extending on each side of and beyond the neck, a sharply beveled element projecting from said handle 55 between said prongs, its front edge being curved to engage with the edge of the bottle cap, and a yoked lever element, formed with said handle, curved upward and outward to extend over and between said prongs in position to engage with the far side of the 60 bottle cap whereby a leverage may be obtained in raising the same.

Signed at New York, in the county of New York and State of New York this 65 twenty-first day of June A. D. 1915.

JOSEF HUTTER.
